Notice of Allowance in U.S. Appl. No. 29/485,934 dated Jul. 21, 2015.

Primary Examiner — Wan Laymon*Assistant Examiner* — Clint A Samuel(74) *Attorney, Agent, or Firm* — Ohlandt, Greeley,
Ruggiero & Perle, LLP(57) **CLAIM**

The ornamental design for a brush handle, as shown and described.

DESCRIPTION

FIG. 1 is a first top perspective view of a brush handle according to the present disclosure;

FIG. 2 is a second top perspective view of the brush handle of FIG. 1;

FIG. 3 is a first bottom perspective view of the brush handle of FIG. 1;

FIG. 4 is a first bottom perspective view of the brush handle of FIG. 1;

FIG. 5 is a side view of the brush handle of FIG. 1, the opposite side being identical thereto;

FIG. 6 is a front view of the brush handle of FIG. 1;

FIG. 7 is a rear view of the brush handle of FIG. 1;

FIG. 8 is a top view of the brush handle of FIGS. 1; and,

FIG. 9 is a bottom view of the brush handle of FIG. 1.

The broken lines shown in the drawings are for illustration only and form no part of the claimed design.
